SIMON LAKE, OF BRIDGEPORT, CONNECTICUT.

SUBAQUEOUS TUNNEL CONSTRUCTION.

SPECIFICATION forming part of Letters Patent No. 730,134, dated June 2, 1903.

Application filed May 31, 1902, Serial No. 109,589. (No model.)

To all whom it may concern:

Be it known that I, SIMON LAKE, a citizen of the United States, residing at Bridgeport, in the county of Fairfield and State of Connecticut, have invented certain new and useful Improvements in Subaqueous-Tunnel Construction, of which the following is a specification.

This invention relates to the construction of that class of subaqueous tunnels which are formed of a series of tubular sections built upon the land and provided each with temporary bulkheads to enable them when launched to be floated to the vicinity of the site upon or beneath the water-bed which they are designed to occupy, then sunk to the required position and connected with the adjacent section or sections, and their bulkheads finally removed to establish communication between such adjacent sections.

The invention has for its object not only to improve the construction of this class of tunnels as actually completed for practical use, but to provide means whereby such tunnels may be built with the greatest safety to the workmen employed in preparing the water-bed therefor, placing the several sections in position, and connecting together and establishing communication between them, and whereby the tunnel may be constructed in much less time than has been practicable with designs heretofore proposed.

The invention consists in the various devices hereinafter described in connection with the accompanying drawings and set forth in the claims annexed hereto.

In the drawings, Figure 1 is a sectional elevation, considerably distorted, for purposes of illustration, showing a completed tunnel under a waterway, indicating the tunnel-tubes in external view and with certain details omitted. Fig. 2 is a sectional elevation, upon a larger scale, of the middle and one end portion of a central tubular section and the contiguous end portion of the adjacent section in telescopic relation therewith, both sections being provided at the ends with bulkheads separating their interiors and also with apparatus employed in the installation of such tunnel-sections in their respective positions; and Fig. 3 is a transverse section on the line 3-3 in Fig. 2, indicating the manner of truss-

ing together two parallel tunnel-sections. Fig. 4 is a sectional elevation similar to Fig. 1, but upon a smaller scale, showing the middle portion of the tunnel with the temporary standing leveling-pipes at the ends of each section and the middle upright shaft or inlet-tube of the central section still remaining in position; and Fig. 5 is a transverse section of the same. Fig. 6 is a detail longitudinal sectional view, upon a greatly-enlarged scale, showing the method of construction of the joints between adjacent sections. Fig. 7 is a plan view showing the middle and end portions of a compound tunnel-section formed of two parallel tubes united by transverse trusses or frames, the tubes being similar in diameter to those represented in Fig. 1.

The opposite banks or shores B of the waterway A are provided, as usual, with sea-walls C, to and through which the land terminal portions D of the tunnel are extended in the usual manner to connect with the intermediate subaqueous portion, shown herein in the connected views as consisting of series of continuously-arranged tubular sections E. Each of these tunnel-sections is formed of a long inner shell consisting of a metallic tube a, encircled by a series of I-angle-rings b, securely attached to the exterior of the same by rivets, and a series of internal L-angle-rings c, similarly secured in position within the interior in a plane transverse to the axis of the tube. Each section is or may be built up of a series of short tubes secured together by rivets similarly to a cylindrical steam-boiler shell, as indicated in Fig. 6, in which the end portion of the right-hand section is shown terminating in a flaring or conical hub a', into which the adjacent cylindrical end of the adjoining section (constituting the spigot of the connection) projects and forms a tight joint, the extreme end of the flared portion a' abutting against the channel-ring a'', disposed near the cylindrical end of said adjoining section. The spaces intermediate the metallic tube a and the I-angle-rings b are filled with cement or artificial stone d, and a similar filling e is interposed between such tube and the rings c, such non-metallic fillings being flush with the outer and inner peripheries of the rings b and c, respectively. A similar filling is introduced

into the annular channel formed between the flared portion a' of the tube a , the end of the tube entering the same and the angle-rings a^2 and b at the opposite ends of such flared portion a' .

- 5 Each tunnel-section is provided with a series of transverse metallic frames or trusses spaced at close intervals apart, and in case the tunnel is formed of two parallel tubes, as 10 indicated in Figs. 3, 5, and 7 of the accompanying drawings, the double tubular sections E , of equal length, are rigidly tied together by such frames or trusses, which latter are shown formed each of a lower or base 15 member f lying beneath and a shorter member g lying upon the tunnel-tubes and united by the inwardly and upwardly inclined side members h , forming in conjunction therewith a frame of trapezoidal form, and intermediate braces i , all of said truss members being not only riveted together, but secured 20 to the shell a and external angle-rings b by bolts or rivets w where their contact with such parts permits. Said trusses are also 25 tied together by longitudinal channel-beams j , extending parallel with the sections E .

A line of piling F , spaced correspondingly with the trusses above described, is driven into the water-bed preferably immediately 30 beneath the center line or axis of each tunnel-tube, so as to support the weight of the latter securely and thereby insure it against injury by settling when traffic is established within the tunnel.

- 35 Each tubular section E is provided near both ends with temporary standing-pipes k , each having a flange at the lower end bolted to a similar flange of the curb l , surrounding an inlet-aperture in the tunnel-tube having 40 a trap-door m normally closed, but adapted to be opened outwardly upon its hinge against a stop-lug n , so arranged that when released the door will drop by its own weight to its seat and automatically close said opening 45 from the penetration of water in case the tube k should be accidentally wrenching off the tunnel-tube by collision therewith of boats or floating matter of any kind upon the surface of the water. Each tube k is provided 50 with a vertical series of horizontal bars o , constituting a ladder for the use of workmen employed in building the tunnel. The central tunnel-sections are also provided each with a larger inlet tube or shaft p , applied 55 and held in place thereon similarly to the end pipes k , and through which the necessary apparatus, supplies, and ballast for carrying on the construction of the tunnel may be lowered into the tunnel-tube beneath by 60 means of a derrick q , arranged upon a common platform r , supported upon said shafts p and carrying in addition to the derrick the hoisting-engine s , boiler t , and motor-driven dynamo u , deriving its motive power from 65 the boiler t , such apparatus, with other devices necessary or useful in connection with the building of the tunnel, being designed

more particularly for assisting in the work of uniting the several sections as well as performing other operations required in completing the tunnel. A trap-door similar to those already described in connection with the pipes k may also be provided for these central shafts, Fig. 7, as well as ladders for ingress and egress of the workmen. Each of 75 the standing pipes or tubes k and p is preferably provided with guys v for staying the same, as is customary in other structures under like conditions.

Each tunnel-section is provided with the usual road-ballast 2 , in which are embedded the sleepers 3 , supporting the railway-tracks 4 , and which contains also a central drainage trough or gutter 5 . Arranged above and at the sides of this roadway are the side conduits 6 , adapted to house gas or water mains, signal pipes or wires, &c., such conduits being surmounted by longitudinal platforms or sidewalks 7 for such uses as may be necessary or desirable.

In addition to the one or more freight-cars 8 with which the central tunnel-tubes would be initially provided for carrying supplies for the building operation each such tube has a work-car 9 , containing an electric motor 95 10 and connected pump 11 , the motor 10 deriving its electric current through a trolley-pole 12 , making electric contact with a conductor-wire 13 , supplied with current from the dynamo or generator u upon the platform r .

9c Each tunnel-section is provided initially with a water-tight bulkhead 14 , having flanges detachably secured by suitable bolts to the webs of the end angle-rings c and provided near the lower edge with apertures having valves 15 . The ends of two sections having been arranged in telescopic relation upon the water-bed, the flexible inlet-pipe 16 of the pump 11 is connected with one of the valves 15 , and the flexible discharge-pipe 17 is similarly connected with an outlet-valve 18 in the tunnel-tube E , when the said valves being opened and the pump put in operation the water confined between the opposed bulkheads and the end portions of their respective tunnel-tubes is forced out, the external pressure upon the exposed outer end of the last-installed section thereby being permitted to force such adjacent tunnel-tubes together and close the space between the flared portion a' of the one and the channel-ring a^2 of the other, into which latter, after the opposed bulkheads have been removed and the adjacent angle-rings c secured together by the bolts 19 , the plastic-cement or artificial-stone 125 filling is injected through the valve 20 , Fig. 6, by means of a suitable pump, as 11 .

In order to a better understanding of the function of the several parts of the tunnel-sections which are employed in placing in position the several sections and in establishing communication between them, I will briefly describe the mode of constructing the tunnel.

The middle tube or tubes (forming a simple

or compound section, as the case may be) are first built upon the shore of a suitable water-way in a convenient position for launching, including in their component parts not only the shell *a* and its external and internal strengthening rings or ribs *b* and *c*, respectively, the attached series of transverse trusses, and the non-metallic filling intermediate said rings, but having also the internal parts, as the road-bed, railway-tracks, conduits, electrical conducting-wires, &c., and the necessary freight and working cars and other necessary apparatus and supplies required in making and sealing the joints with the adjacent sections. The standing tubes *k* and *p* may be added in the course of this stage of the operation. Simultaneously with such work upon the land a suitable trench is dredged in the water-bed, intermediate and preferably equidistant from the opposite shores, suitable for receiving such tunnel-section, and one or more lines of piles are properly driven in such trench, spaced at short intervals, for rigidly sustaining the said central section in its trench. This central section having been temporarily closed at both ends by means of the removable bulkheads 14, it is now launched by means of proper ways and towed to a position directly above the trench previously prepared for it and is then so ballasted as to cause it to sink into the trench, the tops of the tubes *k* and *p* projecting sufficiently above the surface of the water to enable the transit-men to determine the proper adjustment of the section by sighting across them to given objects upon the shores. The dredgings from this middle trench or cut having been removed to some suitable dumping-ground, the dredging of the adjacent cuts for the adjoining tunnel-sections is next effected, the dredgings therefrom being employed to fill in the excavation first made and partially occupied by the central tunnel-section, so as to completely cover the latter, whereby a secure anchorage is provided for the laterally-projecting lower portions of the trapezoidal frames or trusses surrounding the tunnel-tubes as well as for their connecting longitudinal channel-beams. The adjacent tunnel-sections having in the meantime been built similarly to the central section and then launched and floated to the vicinity of their respective excavations, in which are continued the lines of piling begun in the central trench, such newly-built tunnel-sections are similarly sunk into their respective positions and properly lined with the first-installed section, also by the use of their standing pipes *k*, and are brought into telescopic relation with the extremities of the central tunnel-tubes to which they are fitted. The work-car is then moved to one end of the central section and the water confined between the bulkheads 14 pumped out and the bulkheads removed, each from the interior of its respective tube, after which the end angle-rings *c* of the adjacent tubes are

bolted together, either temporarily or permanently, and the filling of non-metallic material injected in the annular space between the flared portion *a'* of one tube and the angle-ring *a''* of the adjoining tube, after the setting or hardening of which filling the valve 20 may be removed and the aperture in the shell *a* closed in any suitable or convenient manner. The joint at the opposite end of this central tunnel-tube may be similarly formed and sealed, each of the adjacent tubes or sections being forced home to effect the metallic closure of the joint by means of the external water-pressure upon the bulkhead at the farther end of the tube from the central tube or section. The succeeding sections are similarly added shoreward in each direction from the central section, a part of the dredgings from the excavation for each section being utilized for filling the trench, inclosing, and covering over the previously-laid section, while the road-bed and the tracks of each tunnel-tube are successively connected with those of the adjoining tubes as soon as internal communication is established between them by the removal of the temporary bulkheads, so that the single working car of each central tube may be used in the formation and sealing of each joint as the several sections are added to the central section.

The leveling-pipes *k* of each tube *E* may, if desired, be removed immediately after the latter has been adjusted in its place in readiness for use in connection with the succeeding tube or section to be installed, or each section may be built with its individual leveling-pipes, all of which may be retained in position until the completion of the tunnel, as indicated in Fig. 4. In like manner the removable bulkheads 14 may be used successively in different tunnel-sections, as their employment is limited to the closing of the ends of the tubes during the launching and floating of such members to their respective positions and their adjustment in respect of and union with the adjacent tubes of the tunnel.

From the foregoing description it will be seen that the present improvement offers, among others, the following important advantages over other forms of tunnel construction: First, it enables the constructors not only to work in the actual building of the tunnel simultaneously at four different points—viz., from the center shoreward in both directions and from each land-terminal in the direction of the sea-wall—but permits of the construction of the individual tunnel-sections upon land at the same time as the trench is being dredged and otherwise prepared for the reception of such sections, and, second, it admits of the carrying on of every part of the work of construction either above the surface of the water or within the tunnel-tubes, and therefore wholly obviates the necessity for employing divers for doing certain portions of the work, as has been required in the

construction of subaqueous tunnels previously devised.

In reference to the driving of piles and cutting them off at the required levels within 5 the trenches I may say that this also may be effected by the use of the apparatus described and claimed in my pending patent application, Serial No. 64,219, filed June 12, 1901, suitably fitted for the purpose in accordance 10 with my designs.

While I have shown and described specifically herein the characteristic features of my present tunnel construction, it is evident that the construction and arrangement of its various 15 parts may be materially altered without departure from the spirit of the invention, and I do not, therefore, wish to be understood as limiting the invention to the specific devices herein described and illustrated.

20 Although the method of procedure devised by me and set forth in the foregoing description is believed to be new and of great utility in the class of engineering work to which it relates, I have not claimed the same herein, 25 as it forms the subject of my pending application, Serial No. 142,640, filed February 9, 1903.

It will be observed that, while the mere opening of one of the valves 15 in the bulkheads 30 14 will permit such portion of the confined water to escape into the interior of the tunnel-tube as will remove the resistance opposed to the pressure upon the extreme end bulkheads, by means of which the adjacent 35 sections are telescoped for closing the junction between them, it is desirable to pump out all of such water in order to form a vacuum between such opposed bulkheads, and thereby add the atmospheric pressure upon such inner 40 bulkheads to the external water-pressure upon the outer end bulkheads for closing the joint.

Having thus set forth the invention, what I claim is—

1. In combination a central tubular tunnel-section provided with a detachable upright tubular shaft or inlet-tube surmounted by a working platform, and series of lateral tubular tunnel-sections each provided with a detachable leveling tube or spar, and connections between the adjacent ends of said sections establishing communication between the same while excluding water therefrom.

2. In combination a central tunnel-section formed of two parallel tubes securely trussed together and provided each with a detachable upright tubular shaft or inlet-tube surmounted by a common working platform provided with hoisting and other power apparatus, series of lateral tunnel-sections each formed 55 of parallel tubes securely trussed together and having detachable upright leveling tubes or spars, and connections between the adjacent ends of said tunnel-sections establishing communication between the same while excluding water therefrom.

3. A subaqueous tunnel composed of a series of telescopic sections each formed of a

metallic cylindrical tube having one end portion flared to receive the adjacent cylindrical end of the next section, and series of transversely-disposed angle-rings within and without said sections with a filling of artificial stone or cement in the intervening spaces between said angle-rings.

4. A subaqueous tunnel composed of series of parallel metallic tubes united by series of transversely-disposed frames or trusses, and two parallel lines of piling driven into the water-bed and spaced longitudinally of the tunnel correspondingly with said trusses resting 80 thereon.

5. A subaqueous tunnel composed of series of parallel metallic tubes united by series of transversely-disposed frames or trusses, and parallel lines of piling driven into the water-bed directly beneath the centers of said tunnel-tubes and spaced correspondingly with 85 said frames or trusses resting thereon.

6. In combination, a series of tubular tunnel-sections having the adjacent end portions 90 fitted together and provided each with a removable water-tight bulkhead, and means applied to one of said bulkheads whereby the water may be drawn from the space between the adjacent bulkheads preparatory to their 95 removal from said sections.

7. In combination a series of tubular tunnel-sections provided in the adjacent end portions with telescopic extremities and with removable bulkheads, and means applied to 100 said bulkheads and the adjacent walls of the tubes whereby the water may be drawn off from the space between adjacent bulkheads and ejected from said sections preparatory to the removal of said bulkheads to open communication between said sections.

8. In combination a series of tubular tunnel-sections having their adjacent end portions fitted together in a close joint, each said section being temporarily closed by means of 110 removable bulkheads, one of each pair of opposed bulkheads being provided with a valved discharge-aperture, and means adapted to be connected with said aperture for drawing off the water from the space intermediate said 115 bulkheads and ejecting it from said sections preparatory to the removal of said bulkheads.

9. In combination a series of metallic tubular tunnel-sections having their adjacent end portions fitted together in a close joint, each 120 being closed by means of a removable bulkhead of which one is provided with a valved discharge-aperture, a pump contained by one of said tunnel-sections having the said apertured bulkhead, and pipe connections between said pump and the discharge-aperture of said bulkhead and between said pump and the exterior of the tunnel-section.

10. In combination a series of tubular tunnel-sections having their adjacent end portions fitted together in a close joint, each said section being temporarily closed by means of removable bulkheads, one of each pair of opposed bulkheads being provided with a valved

- discharge-aperture, a car in one of said tunnel-sections having said apertured bulkhead and carrying a pump and means for actuating the same, and pipe connections between 5 said pump and the discharge-aperture of said bulkhead and between said pump and the exterior of the tunnel-section.
11. In combination a series of tubular tunnel-sections having their adjacent end portions fitted together in a close joint, each said section being temporarily closed by means of removable bulkheads, one of each pair of opposed bulkheads being provided with a valved discharge-aperture, railway-tracks and electrical conductors disposed longitudinally of each tunnel-section, said conductor being connected with an electric-current generator, a car mounted upon the tracks of one of said sections having said apertured bulkhead and carrying a pump and an electric motor coupled thereto for actuating it, an electrical connection between said motor and the electrical conductor of said section, and flexible pipe connections between said pump and the discharge-aperture of said bulkhead and between said pump and the exterior of the tunnel-section.
12. A subaqueous tunnel composed of a series of metallic tubes having their adjacent ends in telescopic relation and formed with an intermediate annular channel, and a filling of plastic material in said channel.
13. A subaqueous tunnel composed of a series of metallic tubes having their adjacent ends in telescopic relation and formed with an intermediate annular channel, and a filling of adhesive plastic waterproof material in said channel.
14. A subaqueous tunnel composed of a series of metallic tubes of which the adjacent ends are formed, respectively, cylindrical and conical and disposed in telescopic relation, and a filling of cement or artificial stone in the annular space intermediate the adjacent ends of said tubes.
15. A subaqueous tunnel composed of a series of cylindrical metallic tubes of which one is provided near the ends with an external angle-ring and the contiguous end of the adjacent tube is flared to receive the end of said first-named tube, said tubes being disposed in telescopic relation with the flared end portion of the one in contact with the external angle-ring of the other, and a filling of cement or artificial stone in the annular space intermediate the contiguous ends of said tubes and said angle-ring.
16. A subaqueous tunnel composed of a series of metallic tubes of which the adjacent ends are formed, respectively, cylindrical and conical and disposed in telescopic relation, each of said tubes having an internal and external covering of cement or artificial stone excepting the opposed telescopically arranged portions at the ends, and a filling of artificial stone in the annular space intermediate the adjacent ends of said tubes.
17. A tubular subaqueous tunnel-section provided intermediate its ends with a detachable shaft or inlet-tube surmounted by a working platform.
18. A tubular subaqueous tunnel-section comprising two or more metallic tubes rigidly trussed together, the same being provided each with a detachable upright shaft or inlet-tube surmounted by and supporting a common working platform provided with hoisting and other power apparatus.
19. A subaqueous tunnel-section consisting of a metallic tube having internal and external series of transversely-disposed angle-rings, with fillings of artificial stone or cement in the spaces included between said angle-rings by the flanges of which they are locked in position.
20. A subaqueous tunnel-section consisting of two or more metallic tubes rigidly trussed together, series of external angle-rings embracing said tubes and secured to the contiguous truss members, series of transversely-disposed internal angle-rings, and fillings of artificial stone or cement intermediate the rings of each said series of angle-rings.
21. A subaqueous tunnel-section consisting of two or more parallel metallic tubes, and a series of transverse trusses embracing the same and binding them together, said trusses extending laterally beyond said tubes at their lower edges.
22. A subaqueous tunnel-section consisting of two or more parallel metallic tubes, and a series of transverse trusses of trapezoidal form embracing and binding the same together, the longer edges of said trusses being disposed beneath said tunnel-tubes.
23. A subaqueous tunnel-section comprising a tube embraced by a series of transverse trusses of trapezoidal form.
24. A tubular subaqueous tunnel-section provided intermediate its ends with a detachable upright tube or shaft, and an upwardly or outwardly opening door at the base of said tube or shaft.
25. A tubular subaqueous tunnel-section provided with a detachable upright tube or shaft, an upwardly or outwardly opening door having a pivot at one side of the base of said upright tube, and a stop within said last-named tube for preventing the opening of said door farther than the vertical plane embracing said pivot.
26. A tubular subaqueous tunnel-section provided with a detachable upright tube or shaft, and an upwardly or outwardly opening door at the base of said upright tube and adapted to close automatically so as to maintain the base of said upright tube normally closed from communication with the tunnel-tube to which the latter is applied.
27. A tubular subaqueous tunnel-section provided with a detachable central upright shaft or inlet-tube surmounted by a working platform, and a detachable upright leveling

tube or tubes at one or both ends of said first-named tube.

28. A tubular subaqueous tunnel-section provided at the opposite ends with removable water-tight bulkheads, one or both of which is provided with a valved aperture.

29. A subaqueous tunnel composed of a series of sections each formed of a metallic cylindrical tube having the ends fitted to those of the adjacent sections, and series of transversely-disposed angle-rings within and

without said sections with a filling of artificial stone or cement in the intervening spaces between said angle-rings.

In testimony whereof I have signed my name to this specification, in the presence of two subscribing witnesses, this 24th day of May, 1902.

SIMON LAKE.
